DRAFT RIGGING

Donald Willison, Cleveland, Ohio, assignor to
National Malleable and Steel Castings Company, Cleveland, Ohio, a corporation of Ohio

Application January 4, 1950, Serial No. 136,669

12 Claims. (Cl. 213—34)

1

This invention relates to railway draft rigging and more particularly to a combination yoke and shock absorbing mechanism.

My invention provides various improvements over the constructions shown in the application of Donald Willison and Hubert L. Spence, Serial No. 790,212 filed December 6, 1947. The invention comprises a novel yoke and draft gear combination which is adapted for use with single stop means of a car structure and which may be readily applied to existing standard car constructions.

In the usual constructions, the draft gear or cushioning mechanism is a separate unit from the yoke which encircles the mechanism and connects the latter to the car coupler. The cushioning mechanism is positioned in the car between front and rear stops against which the mechanism abuts in response to pulling or buffing forces transmitted thereto by the yoke and coupler. My invention provides a draft rigging comprising a unitary cushioning mechanism and yoke arrangement wherein only one of the above named stops is necessary for operation of the device in draft or buff.

The invention also provides a draft gear and yoke combination having the flexibility necessary to permit a coupler to angle substantial amounts in the horizontal directions.

Other features and advantages of the invention will be apparent from the following description taken in conjunction with the drawings in which:

Fig. 1 is a longitudinal horizontal sectional view of an embodiment of the invention.

Fig. 2 is a longitudinal vertical sectional view of the embodiment shown in Fig. 1.

Fig. 3 is a partial view in horizontal section.

Fig. 4 is a view corresponding to Fig. 1 but showing the mechanism angled horizontally and subjected to a pulling force.

Fig. 5 is a view corresponding to Fig. 1 but showing the mechanism angled horizontally and subjected to a buffing force.

Fig. 6 is a transverse vertical sectional view taken along line 6—6 of Fig. 2.

Figs. 7 and 8 are details of the friction shoe.

Referring to the drawings, the center sill 10 of a railway car comprises a pair of spaced longitudinally extending vertical webs 11 and a top connecting portion 12. At the forward end of the center sill is connected the striking casting 13 which is formed with spaced side walls 15 and bottom flanges 16 by means of which the casting is riveted or otherwise securely fastened to webs 11 and horizontal flanges 14 on the sill. Extending inwardly from the rearward ends of side walls 15 are stops 18, each stop having a rearwardly facing vertical surface 20 and forward-facing vertical surface 22.

2

The yoke member 24 comprises a pair of forwardly extending horizontally disposed arms 26 which are joined to a friction housing 28. Each yoke arm 26 is formed with a shoulder or abutment 30 on its outer side for engagement with forward surface 22 on stop 18 to limit rearward movement of the yoke in buff. In neutral or in buffed position of the mechanism, the yoke abutments 30 are in contact with surface 22 on stop 18 as shown in Figs. 1 and 5.

The forward ends of yoke arms 26 are joined by the vertical portions 29 which are provided with key slots 32 for receiving a horizontal key 34 which connects coupler shank 36 to the yoke and which is movable with the coupler shank in buff and draft. A horizontal slot 37 is provided in the coupler shank and is of slightly greater length than the width of key 34 so as to provide a clearance as at 38, thereby enabling relative horizontal angling between the coupler shank and the key. Vertical webs 15 of the striking casting contain horizontal key slots 40 which are of such length as to allow sufficient travel of the key in buff or draft without engaging the forward or rearward ends of the slot. It will be observed that each slot 40 extends into the central portion of stop 18 as at 40a. The webs 11 of the center sill 10 are also slotted as at 41 so that the key is unrestricted by the sills during its travel lengthwise of the car in response to longitudinal movement of the coupler.

The coupler shank has at its end a flat buffing surface 42 for engagement with a follower 44 which is disposed between yoke arms 26 and extends transversely between webs 11 of the center sill. Follower 44 engages the vertical rear surfaces 20 on stops 18 when the mechanism is in neutral position (Fig. 1). The rearward side of follower 44 is provided with a projection 46 having a spherical abutment surface 48. A wedge 50 has a socket 52 for receiving projection 46, thereby permitting universal angling of the follower relative to the wedge.

Friction shoes 54 within housing 28 are urged into engagement with the inner surface 56 thereof by wedge surfaces 57 on wedge 50 and are slide rearwardly relative to the housing against the resistance of inner and outer coil springs 58 and 60. Interposed between the friction shoes and the forward ends of the springs is a plate member 62. The rearward ends of the springs engage an abutment or seat member 64 which is adjustably secured to housing 28 by means of tie bolts 66. Extending rearwardly from the housing is a pair of straps 68 to which the forward ends of bolts 66 are connected. Straps 68 are U-shaped, the middle portion 70 of each having an opening for receiving the threaded end of the bolt 66. The nut 72 which is screwed onto the end of the bolt engages the forward

side of portion 70 and is held against rotation by the parallel sides 74 of the strap. The straps are offset laterally on opposite sides of the longitudinal center line of the housing as viewed in Fig. 1 so as to allow the use of springs of as large diameter as possible and yet hold the vertical and horizontal spacing of the straps to a minimum, thereby providing a maximum clearance between the straps and the adjacent portions of the center sill 10 to allow for both horizontal and vertical angling of the yoke member.

Springs 58 and 60 are preferably under a predetermined amount of initial compression which maintains yoke abutments 30 and follower 44 in engagement with stops 18 as seen in Fig. 1. Also it will be observed that key 34 is shown in engagement with yoke portions 29 at the forward end of slot 32 and with the coupler shank at the rearward end of slot 37. Due to manufacturing tolerances however, the relative position of the parts may vary, whereby follower 44 will be urged rearwardly from its position in Fig. 1 by end surface 42 of the shank and slightly out of contact with stops 18, or key 34 may be loosely held between yoke portions 29 and the shank. The small clearances which may thus be formed otherwise impair the operational characteristics of the mechanism.

To facilitate shipment of the mechanism, the yoke arms 26 are provided along their inner sides with stop elements 76, the ends 77 of which are adapted to be engaged by follower 44 and thus maintain the parts in assembled relationship. When the mechanism is applied to a car, a clearance normally exists between ends 77 and follower 44. Elements 76 in addition serve to reinforce arms 26.

The yoke is supported between webs 11 of the center sill by a strap 78 which is disposed beneath housing 28 and is secured to flanges 14 of sill 10. The coupler shank 36 is supported on carrier portion 80 of the striking casting.

Friction shoe 54 is illustrated in detail in Figs. 7 and 8. It will be seen that the shoe on one side thereof has a pair of angularly disposed friction surfaces 82 which engage the correspondingly arranged surfaces 56 on the inner side of housing 28. The opposite side of the shoe is formed with a pad 84 having a wedge face 86 which is engaged by the wedge face 57 of wedge 50. In the embodiment shown, there are preferably three friction shoes contained within housing 28, all shoes being identical in size and shape.

The operation of the mechanism is as follows:

Upon the application of a buffing force to the mechanism, the end surface 42 of the coupler shank 36 urges follower 44 rearwardly while yoke 24 and housing 28 remain stationary. It will be observed that the yoke and housing are precluded from moving rearwardly by the engagement of abutments 30 on the yoke with forward surfaces 22 on stops 18. Key 34 is carried rearwardly by the coupler shank and moves in this manner without restriction in slots 32, 40, and 41, in the yoke, striking casting, and center sill, respectively. Follower 44 bears against wedge 50 which urges friction shoes 54 outwardly against the inner surface 56 of housing 28 and rearwardly against the resistance of springs 58 and 60. Thus the friction between shoes 54 and the housing in addition to the resistance of the springs, serves to cushion movement of the coupler in buff. Travel of the mechanism in buff is limited by the engagement of follower 44 with the forward end surface 90 of the housing. When

the buffing force ceases to act, the mechanism returns to neutral position as seen in Figs. 1 and 2.

Upon the application of a draft or pulling force to the mechanism the wedging action of wedge 50 and the relative movement of friction shoes 54 against the resistance of the springs is the same as in buff. However, in draft, the yoke and housing are pulled forward by the coupler shank 10 through key 34, while follower 44 remains stationary and in contact with the rear surface 20 of stops 18. Thus, while the wedge and friction shoes remain stationary, housing 28 is drawn forward and seat member 64 is likewise moved forward to compress the springs. Forward movement of the mechanism in draft is limited by the engagement of end surface 90 of the housing with follower 44.

In Fig. 4 the mechanism is shown subjected to a draft force while in horizontally angled position. A feature of the construction resides in the universal movement between follower 44 and wedge 50 which allows the entire mechanism to swivel about follower 44 within the space between webs 11 of the center sill. Swivelling of the mechanism is limited by the engagement of the yoke member with the striking casting as at 92 and 94. Within the range of horizontal angling of the yoke member, full surface engagement exists between the coupler shank and key 34. A certain amount of additional horizontal angling is provided between the coupler shank and the yoke member due to the clearance between key 34 and slot 37 in the shank, which allows the coupler to corner on the key as at 96. The total angling of the coupler thus provided is sufficient to meet the Association of American Railroads requirements for horizontal coupler swivelling.

In Fig. 5 is illustrated the manner in which the mechanism provides for coupler angling under a buffing load. In this case the yoke remains centered between webs 11 of the car sill with abutments 30 in contact with the forward surfaces 22 on stops 18. As the coupler angles follower 44 pivots in socket 52 of the wedge while maintaining full surface contact with the end surface 42 of the coupler shank. Key 34 moves with the coupler shank and assumes an angled position in slots 32, 40 and 41, in the yoke, striking casting, and center sills, respectively. The amount of coupler angling permitted by this arrangement is limited by the engagement of the coupler shank with the inner surface 98 of yoke arm 29. It will be observed that each yoke arm 29 is relieved as at 99 to allow for angling of the coupler shank. The amount of coupling angling thus provided under a buffing load is also sufficient to meet the Association of American Railroads requirements for horizontal swivelling.

The terms and expressions which I have employed are used in a descriptive and not a limiting sense, and I have no intention of excluding such equivalents of the invention described, or of portions thereof, as fall within the purview of the claims.

What I claim is:

1. In a combination yoke and shock absorbing mechanism, a member for operative connection to a car coupler, said member comprising a housing portion, friction shoes slidably engaging the inner surface of said housing, a wedge for actuating said shoes, spring means for opposing movement of said shoes relative to said housing, follower means having a spherical abutment re-

ceived in a corresponding socket in said wedge to enable angling of said follower means relative to said member, and stop lugs on said member positioned forwardly of said follower means for engagement with stop means on a car structure to preclude rearward movement of said member in buff.

2. In a combination yoke and shock absorbing mechanism, a yoke member, said member comprising a housing portion, friction means slidably associated with said housing portion, a follower member in engagement with said friction means, a key for operatively connecting said yoke member to a car coupler, said yoke member having stop lugs for engagement with stop means on a car structure to preclude rearward movement of said member in buff, said yoke member being slotted to permit rearward movement of said key relative to said yoke member.

3. A combination yoke and shock absorbing mechanism comprising a rearwardly movable follower, a forwardly movable yoke member and cushioning means carried by said yoke member, said means being actuated during rearward movement of said follower and during forward movement of said yoke, said follower having a transversely extending portion for engagement with the rearward side of stop means on a car structure to preclude forward movement of said follower in draft, said yoke member having laterally extending integral stop lugs disposed forwardly of said follower, said lugs having vertical plane surfaces for engaging the forward side of stop means on the car structure to preclude rearward movement of said member in buff.

4. In a combination yoke and shock absorbing mechanism a rearwardly movable follower and a forwardly movable yoke member, said yoke member having a housing portion at one end thereof and arms at the other end thereof, said arms being adapted for operative connection to a car coupler, friction means in said housing portion adapted to be moved rearwardly relative to said housing by said follower during movement of the coupler in buff, said follower being arranged for engagement with one side of stop means on a car structure to preclude forward movement of said follower in draft, said yoke arms having stop lugs for engagement with the other side of the stop means on the car structure to preclude rearward movement of said yoke member in buff, said yoke member and housing portion being movable forwardly relative to said friction means during movement of the coupler in draft.

5. A combination yoke and shock absorbing mechanism comprising a rearwardly movable follower member and a forwardly movable yoke member, said yoke member comprising a housing portion for receiving friction developing means and arms at the forward end of said housing portion for operative connection to a car coupler, said follower member being arranged for engagement with the rearward side of stop means on a car structure, said arms having stop means for engagement with the forward side of the stop means on the car structure to preclude rearward movement of said yoke member in buff.

6. In a combination yoke and shock absorbing mechanism, a rearwardly movable follower and a forwardly movable yoke member, said follower having end portions for engagement with one side of stop means on a car structure to preclude forward movement of said follower in draft, said yoke member having stops at the sides thereof for

engagement with the other side of the stop means on the car structure to preclude rearward movement of said member in buff, said member being slotted for receiving a key for connecting said member to a coupler shank.

7. In a railway draft rigging a yoke member comprising a housing portion, a pair of arms extending forwardly from said housing portion for operative connection to a car coupler, and spring carrying means extending rearwardly from said housing portion, spring means carried by said spring carrying means, friction shoes engaging the inner surface of said housing and being movable relative to said housing portion against the resistance of said spring means, a wedge for actuating said shoes, follower means engaging said wedge and being movable rearwardly relative to said yoke member, said follower means being adapted for engagement with the rearward side of stop means on a car structure to preclude forward movement of said follower in draft, said yoke member being movable forwardly relative to said shoes, wedge and follower means, said yoke arms having lugs for engagement with the forward side of the stop means on the car structure to preclude rearward movement of said yoke member in buff, said yoke arms being slotted to receive a horizontal key for connecting a car coupler to said yoke member.

8. In a combination yoke and shock absorbing mechanism a yoke member having a forward portion adapted for operative connection to the shank of a car coupler to enable horizontal angling of said coupler relative to said yoke member, a follower for engagement with the end surface of said coupler shank, said follower having a rearward projection formed with a spherical abutment surface, and a member having a socket for receiving said abutment surface to enable angling of said follower in response to angling of said coupler shank.

9. In a combination yoke and shock absorbing mechanism a yoke member having a housing portion, friction shoes slidably engaging the inner surface of said housing portion, a wedge for actuating said shoes, said wedge having a socket on its forward side, a follower having a rounded abutment portion received in said socket to enable angling of said follower relative to said yoke member, said follower engaging one side of stop means on a car structure to preclude forward movement of said follower in draft, and lugs on said yoke member positioned forwardly of said follower and engaging the other side of the stop means on the car structure to preclude rearward movement of said yoke member in buff.

10. A striking casting for attachment to a car structure, comprising a pair of spaced rearwardly extending walls for receiving a yoke member, inwardly extending stops at the rearward ends of said walls having forward and rearward vertically extending abutment surfaces, the forward surfaces of said stops being adapted for engagement with lugs on the yoke member to preclude rearward movement of the member in buff relative to said casting, the rearward surfaces of said stops being adapted for engagement with follower means associated with said member to preclude forward movement of the follower in draft.

11. A yoke member for a unitary yoke and shock absorbing mechanism including friction elements, said member, comprising a housing portion for containing the friction elements of the mechanism, said housing portion having an inner

surface adapted for longitudinal slidable engagement with the friction elements of the mechanism, arms extending forwardly from said housing portion, the forward ends of said arms being arranged for operative connection to a car coupler, and abutments integral with said arms adapted for engagement with the forward side of stops on a railway car structure to limit rearward movement of the yoke member.

12. A yoke member for a unitary yoke and shock absorbing mechanism including friction means, said yoke comprising a housing portion for receiving the friction means of said mechanism, a pair of vertically spaced arms extending forwardly from said housing portion, vertical portions for joining the forward ends of said arms, said portions being slotted for receiving a key for connecting said yoke member to a car

coupler, said arms having laterally extending abutments at the sides thereof adapted for engagement with the forward side of stops on a railway car structure to limit rearward movement of said yoke member.
